UNITED STATES PATENT OFFICE.

NATHAN S. MEYER, OF NEW YORK, N. Y.

BUTTON.

1,407,945.

Specification of Letters Patent. Patented Feb. 28, 1922.

Application filed February 24, 1921. Serial No. 447,529.

To all whom it may concern:

Be it known that I, NATHAN S. MEYER, a citizen of the United States, residing at New York, in the county New York and State of New York, have invented certain new and useful Improvements in Buttons, of which the following is a specification.

In the use of buttons of special design particularly buttons for uniforms bearing special insignia, it is important that they be attached to the garment so that they will lie as flat upon the surface of the garment as possible and also be maintained in fixed positions relative to the different parts of the garment so that the insignia will always stand in proper position and the buttons show neatly and smoothly upon the garment. The object of my invention is to provide a button which, when attached, will possess the advantages above referred to, all as will be hereinafter more fully described and claimed.

Referring to the accompanying drawings which are made a part hereof and on which similar reference characters indicate similar parts,

Figure 1 is a perspective view of the underside of a button constructed in accordance with my said invention, and

Figure 2, a central section through the same.

The button itself is preferably of metal and consists of two plates 10 and 11 secured together at their edges by inter-engaging flanges, or in any approved manner. Plate 10 is the base plate carrying the shank 12, and plate 11 is the outer plate giving shape to the button and on which the design is formed.

The button in the main is, or may be, of the special construction shown, or of any approved construction, the plate 11 being stamped out of metal of appropriate thickness and of any design which it may be desired to imprint thereon.

Plate 10 is formed concaved or tapering inward toward the center and with a central depression. It has a shank 12 consisting of a wire which is extended through perforations in the bottom of said depression and has its points turned outwardly and secured in position by solder 13. Said shank 12 is formed with two loops or eyes 14, formed by bending the center of the shank inwardly until it is practically doubled on itself, the

points of the loops extending but slightly beyond the face of plate 10 as shown.

In attaching the button, the thread is passed through the eyes 14 of shank 12, the button being first appropriately positioned on the garment. The eyes 14 being a distance apart and separated by the bend in the wire of the shank, will afford a support to the button which will prevent it from twisting or turning out of its fixed position and thus the button is maintained so that the insignia or design thereon will always occupy the proper position relative to the other parts of the garment. The shank being mounted in the depressed central portion of the plate, also enables the button to lie closely and flat upon the garment, insuring that it will always be held neatly and not permitted to hang or swing as when a protruding eye or shank is used, as in buttons of common construction.

Having thus fully described my said invention what I claim as new and desire to secure by Letters Patent is:

1. A button comprising a body and a shank consisting of a single wire located in a depression on the body, said wire being substantially concealed in said depression and being bent in a plurality of downwardly-extending loops to form thread-holding means projecting but slightly beyond the level of the rim on the body of the button, substantially as set forth.

2. A button having a central depression in its underside, and having its underside concaved from the rim toward the depression, a shank secured in said depression and substantially beneath the level of said rim, substantially as set forth.

3. A button formed with a central depression on its underside, a shank secured in said depression and formed of a wire looped or bent centrally to form separated thread-holding eyes, the points of said loops being positioned but slightly outside the inner face of the button, substantially as set forth.

4. A button comprising stamped plates secured together, the inner plate having a central depression, a shank secured in said central depression and formed of wire looped to form thread-holding eyes separated one from another, said eyes being but slightly outside the inner face of the button, substantially as set forth.

5. A button comprising two plates and a shank, the inner plate being concaved and the outer plate formed to show the design of the button, said inner plate also having a 5 central depression in which said shank is mounted, said concaved formation and said depression substantially concealing the shank, and the shank being secured in place by fusible metal, substantially as set forth.

In witness whereof, I have hereunto set 10 my hand and seal at New York, New York this 19th day of February, A. D. nineteen hundred and twenty-one.

NATHAN S. MEYER. [L. s.]
